ATTORNEY.

UNITED STATES PATENT OFFICE.

JAMES FALLOWS, OF PHILADELPHIA, PENNSYLVANIA.

TOY CAR, WAGON, OR OTHER VEHICLE.

SPECIFICATION forming part of Letters Patent No. 273,046, dated February 27, 1883.

Application filed December 6, 1882. (No model.)

To all whom it may concern:

Be it known that I, JAMES FALLOWS, a citizen of the United States, residing in the city and county of Philadelphia, State of Pennsylvania, have invented a new and useful Improvement in Toy Cars, Wagons, or other Vehicles, which improvement is fully set forth in the following specification and accompanying drawings, in which—

10 Figure 1 is a top or plan view of the portion of the toy embodying my invention. Fig. 2 is a side elevation of a car having my invention applied to it. Fig. 3 is an end view thereof.

Similar letters of reference indicate corresponding parts in the several figures.

My invention relates to improvements in the construction of tin toys of the order of cars, wagons, or other vehicles; and it consists in making the floor, platforms, dashers, axle-bearings, and steps of the vehicle of one piece of metal, whereby a strong, durable, and inexpensive article is produced, as will be hereinafter set forth.

Referring to the drawings, A represents the body of a vehicle of the form of a car, and B represents the floor to which the body is secured. C represents the platforms of the vehicle; D, the dashers; E, the steps, and F the journal or axle bearings of the wheels G. The floor, platforms, dashers, steps, and axle-bearings are formed of one piece of metal, the blank being substantially of the shape shown in Fig. 1, the parts thereof adapted for the platforms and dashers being longitudinal continuations 35 of the part adapted for the floor, the parts adapted for the axle-bearings projecting laterally from the floor part, and the part adapted for the steps projecting laterally from the parts adapted for the platforms. The several parts 40 may be cut of plain or ornamental form. The parts for the dashers are bent upwardly, and those for the steps and axle-bearings bent downwardly, the parts for the steps being further bent into L shape, after which the body

A of the vehicle is connected with the floor 45 B, and the vehicle painted or otherwise ornamented or finished.

It will be seen that, as the several parts B C D E F enumerated are made of one piece of metal, I avoid the employment of separate 50 pieces, and the consequent soldering and joints; wherefore there is a saving of material, labor, time, and expense, and the production of a stronger, cheaper, and better article.

The bending of the parts for the dashers, 55 steps, and axle-bearings may be simultaneous with the cutting or shaping of the same in conjunction with the floor part, or a distinct operation therefrom, and the floor may have formed in it at either time openings a to receive the 60 attaching-lugs of the bottom of the body of the vehicle.

It is evident that the vehicle may be formed with a platform, dasher, and steps integral with the floor at one or both ends thereof, as 65 desired.

Having thus described my invention, what I claim as new, and desire to secure by Letters Patent, is—

1. In a toy vehicle, the floor, platforms, dashers, steps, and axle-bearings formed of one 70 piece of sheet metal bent into shape, substantially as and for the purpose set forth.

2. The body, in combination with the floor, platform, dashers, steps, and axle-bearings, 75 constructed of one piece of sheet metal bent into shape, and forming an improvement in toy vehicles formed of metal.

3. A blank for sheet-metal toy vehicles, consisting of the central part, B, the end parts, C 80 D, and the side parts, E F, said end parts and side parts being adapted to be bent into shape, substantially as set forth.

JAMES FALLOWS.
